(57) **CLAIM**

The ornamental design for a disc tray, as shown and described.

DESCRIPTION

FIG. 1 is a top, front, and right-side perspective view of a disc tray, showing my new design;

FIG. 2 is a front elevational view thereof;

FIG. 3 is a rear elevational view thereof;

FIG. 4 is a right-side elevational view thereof, the left-side being a mirror image thereof;

FIG. 5 is a top plan view thereof;

FIG. 6 is a bottom plan view thereof; and,

FIG. 7 is a top plan view thereof shown with labels attached thereto, the broken line showings of the labels are for environmental purposes and form no part of the claimed design.
